UNITED STATES PATENT OFFICE.

JACOB PFENNINGER, OF ST. LOUIS, MISSOURI.

DESIGN FOR A BRETZEL.

SPECIFICATION forming part of Design No. 21,450, dated April 5, 1892.

Application filed February 1, 1892. Serial No. 419,992. Term of patent 14 years.

To all whom it may concern:

Be it known that I, JACOB PFENNINGER, a citizen of the United States, residing at St. Louis, in the State of Missouri, have invented and produced a new and original Design for Bretzels, of which the following is a specification, reference being had to the accompanying drawing, showing a part thereof.

The essential features of my design consists in the series of radially-arranged depressions provided in the face of the outer curved portion of a bretzel.

In the drawing is shown a plan view of a bretzel, illustrating my design.

15 1 represents a body of a single piece of curvilinear outline and having a twist 2 formed in its length and the ends of said body projecting beyond the same and in full view of the observer. The said body varies in size, 20 gradually diminishing from the center thereof to the ends.

A bretzel designed as above described will

be provided with three triangular-shaped openings 3, formed by curved and straight lines.

The twist 2, formed in the body 1, is near the lower edge of the said body and at the middle of the same, giving the said bretzel a uniform shape and regular in outline. Upon the surface of said body are formed radially-arranged depressions 4, which give the said body an ornamental appearance.

Having now described my new design, what I claim as new, and desire to secure by Letters Patent, is—

The design for a bretzel, substantially as herein described and shown.

In testimony whereof I affix my signature in presence of two witnesses.

JACOB PFENNINGER.
